DESIGN FOR A TIRE

Philip H. Ober, Mansfield, Ohio

Application July 19, 1933. Serial No. 48,755

Term of patent 7 years

To all whom it may concern:

Be it known that I, PHILIP H. OBER, a citizen of the United States of America, residing at Mansfield, in the county of Richland and State of Ohio, have invented a new, original, and ornamental Design for a Tire, of which the following is a specification, reference being had to the accompanying drawing forming a part thereof.

I claim:—

The ornamental design for a tire as shown.

P. H. OBER.
